UNITED STATES PATENT OFFICE

LEROY E. WILLIAMS, OF EDGERTON, WISCONSIN, ASSIGNOR TO HIGHWAY TRAILER COMPANY, OF EDGERTON, WISCONSIN, A CORPORATION OF WISCONSIN

PORTIÈRE-TYPE COVER FOR DUMPING BODIES

Application filed June 22, 1928. Serial No. 287,455.

This invention has to do with dump body vehicles of the type designed for tilting or rolling laterally for discharging a load, and more particularly to covering means for enclosing the load-carrying space of the body. The primary object of the present invention is to provide a cover of improved, simplified construction which may be economically manufactured. Another object is to provide covering means of flexible material arranged to be longitudinally extended over the load-carrying space of the body or disposed in compact form at one end of the body to permit free and unrestricted dumping action of the body when it is tilted to either side for discharging its load. A further object of this invention is to provide a cover consisting of two or more flexible cover sections each adapted to enclose a substantial portion of the load-carrying space of the body and operable independently of each other to expose a limited portion of said load-carrying space at will. It consists in certain features and elements of construction, as herein shown and described as indicated by the claims.

In the drawings:

Figure 1 is a diagrammatic end view of a vehicle body equipped with a cover embodying the present invention. Figure 2 is a fragmentary view in side elevation with parts broken away to show details of construction and for condensation of the view.

Figure 3 is a cross-sectional view through the cover and support taken as indicated at line 3—3 on Figure 2.

Figure 4 is an enlarged fragmentary detail view in elevation showing the manner of supporting the cover.

Figure 5 is an enlarged detail view looking at the inside of one of the cover sections which is provided with an end flap.

Figure 6 is a detail sectional view taken at line 6—6, on Figure 5.

Figure 7 is a fragmentary view showing details of construction.

For the purpose of illustration I have shown my invention as applied to an upwardly open vehicle body indicated at 1, which is provided with the usual curved rockers, 2,

mounted on transverse cross rails, 3, of the vehicle frame. These parts are of conventional design especially suited to vehicle construction wherein the body is rolled toward either side and thus tilted for discharging its load. As will be noted from the drawings, the covers for the body are supported independently thereof so as not to, in any manner, alter its center of gravity thus insuring proper dumping action. It is to be understood that the vehicle is provided with the usual mechanism for locking the body in upright position, and a detail description thereof is unnecessary as it forms no part of the present invention.

A pair of upwardly extending A-frames, 4, are mounted on the vehicle frame adjacent the opposite ends of the body. These frames preferably are castings and are each provided with integral, centrally disposed, upwardly open sockets, 5, which are offset longitudinally of the vehicle. In these sockets are removably mounted vertical uprights, 6, which are detachably fixed in place by set screws, 7. On the upper ends of the uprights, 6, are removably mounted brackets, 8, which support a pair of transversely spaced, longitudinally extending ridge poles 9, above the load-carrying space of the body. The brackets, 8, are of "goose-neck" formation and are offset so that the ridge pole members, 9, extend for a distance longitudinally beyond the uprights, 6, as shown in Figure 2. Set screws, 10, are provided for removably securing the brackets, 8, in place on the uprights, so that the overhead structure may be removed from the body at two separate places, i. e., by bodily removing the uprights, 6, with the overhead structure from the socket, 5, by releasing set screws, 7, or by removing the brackets, 8, with the overhead structure from the upper ends of the uprights, 6, on releasing the set screws, 10.

Separate covers are provided for each side of the body, supported on the respective ridge poles and operative independently of each other. It will be understood that the cover for each side of the body may be of a single section, or may be made up in a plurality of sections, whichever is desirable or more con-

venient for a particular size and style of body. The covers, herein indicated at 12, are of flexible sheet material such as canvas, the entire marginal edges of which are partially stiffened or reinforced by suitable material such as rope, or, as herein indicated, narrow fabric straps, 13. Each of the covers is provided with a plurality of transversely extending reinforcing straps, 14, the upper 10 ends of which are folded back upon themselves to form loops in which are held rings, 15, of D-shape. Each of these rings, 15, is detachably engageable with the hook portion, 16, of a ring, 17, which is of S-shape formation and is slidably mounted on the ridge pole, 9, so that the covers may be quickly and 15 easily extended over the load-carrying space of the body or bunched in compact form at one end of the body as shown at the left hand portion of Figure 2; thus the covers will be completely clear of the body when the same is to be rolled laterally for dumping its load. The alternate transverse reinforcements, 14, are provided with extensions, 19, which depend beyond the lower edge of the cover and 20 are detachably engaged by friction buckles, 20, secured to the body for drawing the flexible covers taut and retaining them in position when they are extended over the load-carrying space of the body. It will be seen that the cover construction is such that, in no 25 case is there a direct pull on the flexible cover proper, the strain being taken by the reinforcements, 13 and 14; and when the cover is secured in closed position the pull on the extensions, 19, is transmitted directly through 30 to the straps, 14, and supporting rings to the ridge poles.

The outer ends of the covers are provided 35 with end flaps, 22, designed to enclose the opening between the cover proper and the ends of the body, as shown in Figure 1. These flaps are each provided with flexible tying members, such as ropes, 23, for securing together the flaps of the opposite cover sections, on the outside of the upright, 6, thus 40 completing the enclosure of the body. These ropes also serve for tying the covers in gathered form to the uprights, 6.

45 Extending centrally of and longitudinally over the ridge poles in registration with the space between them is a shed member, 25, having end supports, 26, removably mounted in brackets, 8, by means of set screws, 27, as shown in Fig. 7. As may be seen, the shed member is supported above and in spaced relation to the ridge poles to permit free movement of the S-rings, while serving to complete the body closure.

50 It will be clear that the overhead structure may be removed bodily or in portions, from the body, as desired. By constructing the cover-supporting structure in this manner the parts may be freely handled and the 55 cover structure may be readily and completely

taken down when not in use. Frequently this type of vehicle is permitted to remain out-of-doors for long periods and in order not to subject the canvas cover to unnecessary weathering, it is therefore particularly desirable to be able to quickly remove it from the vehicle. This may be easily accomplished by merely disengaging the rings, 15, from the hooks, 16. As may be seen from Figure 1, the overhead structure is mounted sufficiently high above the body to permit the same to be tilted without obstruction to either side for discharging its load,—the path of travel of one edge of body being indicated in dotted lines in Figure 1.

70 I claim:—

75 1. In combination, an upwardly open body having side walls and end walls, and mounted for tilting in a direction parallel to said end walls, a bar extending above the body from end to end and supported independently thereof and a flexible cover dimensioned to extend from the bar to one side of the body with attaching devices connecting said cover to the bar at intervals and slidable on said bar to permit gathering the cover; said bar having a portion which extends beyond one 80 end of the body sufficiently to accommodate the gathered cover at a position clear of said body to avoid interference with the tilting movement of the latter.

85 2. In combination, an upwardly open body having side walls and end walls and mounted for tilting in a direction parallel to said end walls, a ridge pole extending above the middle of the body from end to end and supported independently thereof and a flexible cover dimensioned to extend slopingly from the ridge pole to one side of the body with attaching devices connecting said cover to the ridge pole at intervals and slidable on said ridge pole to permit gathering the cover; said ridge pole having a portion which extends beyond one end of the body sufficiently 90 to accommodate the gathered cover at a position clear of said body to avoid interference with the tilting movement of the latter.

95 3. In combination, an upwardly open body having side walls and end walls and mounted for tilting in a direction parallel to said end walls, a bar extending above the body from end to end and supported independently thereof and a plurality of flexible cover sections dimensioned to extend beyond the bar to one side of the body with attaching devices connecting said covers to the bar at intervals and slidable on the bar to permit gathering the cover sections; said bar extending beyond both ends of the body sufficiently 100 to accommodate half of the sectional cover in gathered form clear of said body to avoid interference with the tilting movement of the latter.

105 4. In combination, an upwardly open body

having side walls and end walls and mounted for tilting in a direction parallel to said end walls to either side of its middle load carrying position, a double ridge pole extending above the body from end to end and supported independently thereof and flexible covers dimensioned to extend slopingly from the ridge poles respectively to opposite sides of the body with attaching devices connecting said covers to the ridge poles at intervals and slidably thereon to permit gathering of the covers; said ridge poles having portions which extend beyond the end of the body sufficiently to accommodate the gathered covers in position clear of the body to permit tilting the latter in either direction.

5. In the combination defined in claim 1 the support for the bar being engaged therewith at the extreme end of its extending portion leaving the bar clear for sliding of the curtain thereon to a point beyond the end of the body.

LEROY E. WILLIAMS.
